Frank Kent
ATTORNEY

UNITED STATES PATENT OFFICE

JAMES PETERS, OF BOSLYN HEIGHTS, NEW YORK, ASSIGNOR TO THE TURBO-MIXER CORPORATION, OF NEW YORK, N. Y., A CORPORATION OF NEW YORK

MIXING APPARATUS

Application filed March 28, 1929. Serial No. 350,491.

My invention relates to mixing apparatus, and especially to an arrangement or mechanism by which the mixer proper may easily be moved to and from operative position in a tank containing the materials to be mixed.

The apparatus is adapted for mixing a great variety of materials. A sufficient example of its utility is in the manufacture of paints, where the pigments, oil or other materials are measured into tanks and it is desired to position a tank at the mixer and readily lower the mixer into position, and remove it after mixing is completed.

The characteristics and advantages of the invention are further sufficiently explained in connection with the following detail description of the accompanying drawing, which shows one representative embodiment. After considering this example, skilled persons will understand that many variations may be made without departing from the principles disclosed, and I contemplate the employment of any structures that are properly within the scope of the appended claims.

25 In the drawings:

Fig. 1 is a side elevation of an apparatus embodying the invention in one form.

Fig. 2 is a top plan.

The mechanism is supported on or about a frame or standard 1 which may, as shown, be of generally channel section in horizontal planes, although the frame structure may vary greatly. In one preferred form, as shown, the frame is a casing including a base 2, side walls 3 and a front wall 4.

The mixer proper may be of any suitable type. As shown, the mixer is of what is known as the "turbo" type, including a rotor 5 surrounded by a generally annular deflector 6.

The deflector is carried by upright struts 7 from an annular frame 8. On this frame are uprights 9 supporting the casing of an electric motor 10. A shaft 11 which may be the motor shaft, or connected thereto, carries the rotor 5. The entire mixer structure, including the mixer proper, frame 8 and motor 10, are supported for vertical movement by pairs of arms 12 and 13. The upper arms 12 are pivotally mounted at 14 on side walls of the standard, and at their other ends are piv-

totally connected at 15 to the motor casing or a frame member supporting the casing. The lower arms 13 are also pivotally mounted at 16 on the side walls of the standard, and at their other ends are pivotally connected at 17 to frame 8. The pivot locations are such as to provide for parallel motion; that is, the mixer structure, and especially shaft 11, are maintained in vertical position as they are moved up and down.

To facilitate movement of the mixer, counterbalancing means is provided, consisting of a counterweight 20 carried by a chain 21, running over a pulley or sprocket 22 and having its other end connected to a crossbar 23, this crossbar being connected to the two arms of either pair of arms—specifically, as shown, to the lower arms 13. The sprocket 22 is carried on a shaft 24 mounted in bearings at the upper ends of the side walls of the standard.

The counterweight may be adjustable, as by providing a plurality of separate weights 20, on the general plan of scale weights, so that an accurate counterbalance may be provided for mixing apparatus of any weight.

The mixing apparatus may be raised and lowered by moderate manual force supplied to any convenient point, such as frame 8 on the arms 12 or 13. It is raised to the position shown in dotted lines in Fig. 1 to permit a tank, such as 30, containing the materials to be mixed, to be positioned below the mixer, and then the mixer is lowered to a suitable position such as shown in full lines; the motor is operated, and after mixing is completed the mixing apparatus is raised, the tank removed and another tank positioned for mixing, and so on.

I claim:

1. Mixing apparatus comprising a stationary frame, a movable frame, a mixer supported thereby including a rotor and a substantially vertical rotor shaft, a motor on the movable frame connected to the shaft, and a parallel linkage connecting the movable frame to the fixed frame, whereby the mixer may be moved in parallel alignment into and from a tank containing mixable materials, the mixer also including a gener-

ally annular deflector located about the rotor, and uprights connecting the deflector to the movable frame.

2. Mixing apparatus comprising a standard, parallel arms pivotally connected to the standard, a movable frame pivotally connected to said arms, a motor in an upward location on the movable frame, and a mixer supported in a lower position by the movable frame, the mixer comprising a rotor and a vertical shaft connecting it to the motor, and a deflector structure about the rotor and upright members connecting the deflector to the movable frame.

15 3. Mixing apparatus comprising a stationary standard, upper and lower parallel arms pivotally connected to the standard, a movable frame pivotally connected to said arms, a motor in an upward location on the movable frame, and a mixer supported in a lower position by the movable frame, the mixer comprising a rotor and a vertical shaft connecting it to the motor, and a deflector structure about the rotor and upright members connecting the deflector to the movable frame.

4. A mixing apparatus for general commercial mixing, comprising a column adapted for floor support, a movable frame, parallel arms pivotally connected to the column and movable frame to guide the latter in substantially vertical movement, a counterweight and a connection therefrom to support the weight of the arms, movable frame and parts thereon, a motor mounted at an upper position on the movable frame, a shaft extending down from the motor, a rotary turbo-impeller at the lower end of the shaft, a stationary bladed deflector about the impeller, and arms extending downward from the movable frame and supporting the deflector, the mixer comprising the impeller and deflector being adapted for practically vertical movement into and out of a mixing tank located on the floor adjacent the column.

In testimony whereof I affix my signature.

JAMES PETERS.
